5 Claims. (Cl. 260—666)

This invention relates to the reforming of a natural cyclohexane-containing fraction. In one aspect the invention relates to the production of additional methylcyclopentane. In one of its aspects the invention relates to the production of high purity cyclohexane.

The reforming of a natural cyclohexane-containing fraction to produce methylcyclopentane is disclosed in U.S. Patent No. 3,009,002, issued to Carl M. Kron, November 14, 1961. In this patent there is disclosed a process for producing high purity cyclohexanes from naturally occurring cyclohexane which comprises a combination of related steps of the character such that there is produced relatively cheaply cyclohexane of a high purity (98 percent) and a benzene concentrate. The process involves as an essential step the catalytic conversion of the natural cyclohexane to benzene and to methylcyclopentane. Also included in the process is the recovery of the methylcyclopentane and benzene, and the subsequent hydrogenation of benzene to cyclohexane and isomerization of methylcyclopentane to cyclohexane.

Under such conditions, the natural cyclohexane is converted in a catalytic reforming zone together with and in the presence of a reformer zone feedstock, for example low end point reforming feedstock or gasoline, to produce not only more methylcyclopentane than can be expected from the added cyclohexane but also more benzene than can be accounted for by the natural cyclohexane in the feed. It has been found that subjecting cyclohexane to reforming conditions results in conversion of 15 to 20 percent of the cyclohexane to methylcyclopentane with a majority of the remainder being converted to benzene. Since the ultimate desired product is generally high purity cyclohexane which requires methylcyclopentane for its production in the isomerization zone, it would be most desirable to decrease the conversion of the cyclohexane to benzene and to increase the conversion of the cyclohexane to methylcyclopentane in the reforming operation.

It is an object of the invention to provide a process for the reformation of a natural cyclohexane-containing fraction.

It is another object of the invention to provide a method for the production of methylcyclopentane.

It is yet another object of the invention to provide a process for the production of cyclohexane.

It is another object of the invention to increase the conversion of cyclohexane to methylcyclopentane in a reforming zone.

It is another object of the invention to provide a method for the decrease in the production of benzene from the catalytic reforming of cyclohexane to methylcyclopentane and benzene.

These and other objects of the invention will be readily apparent to those skilled in the art from the following disclosure, claims and drawing.

These objects are broadly accomplished in a process for reforming a natural cyclohexane-containing feed which comprises reforming said feed in the reforming zone to produce an effluent containing benzene and methylcyclopentane, recovering benzene from said effluent and recycling said benzene to said reforming zone.

In another aspect of the invention, the methylcyclopentane recovered from the reforming zone effluent, which stream contains benzene, which is detrimental when present therein above a certain minimum amount,

2

is introduced into a benzene hydrogenation zone and the effluent therefrom is introduced into an isomerization zone to produce high purity cyclohexane.

The feed for the reforming zone may contain a number of hydrocarbons other than impure cyclohexane and usually is a mixed feed of natural C₆ hydrocarbons containing isohexanes, normal hexane, benzene, methylcyclopentane, and cyclohexane as well as certain heptanes, including dimethylpentanes.

In general, the feed to the reforming zone has been demethylcyclopentanized, thus obtaining a natural cyclohexane concentrate containing dimethylpentanes (which boil at approximately the same temperature as cyclohexane), with this concentrate being passed to a catalytic reforming zone. The reformer effluent is dehexanized, dehexanized and the hexanes-containing stream is then subjected to solvent extraction, or the like, for the separation of benzene and methylcyclopentane fractions from the remaining reformat. The benzene-containing extract from the solvent extraction zone is then recycled to the reformer with the raffinate being passed into a dehexanizer for the removal of normal and isohexanes and the recovery of methylcyclopentane. The methylcyclopentane, containing a small percentage of benzene, is passed through a benzene-hydrogenation and methylcyclopentane-isomerization operation from which the effluent is treated by conventional means to obtain a high purity cyclohexane product.

In another embodiment the natural cyclohexane-containing fraction is first dehexanized with the hexane fraction thus obtained being deisohexanized, and the deisohexanized fraction is then demethylcyclopentanized resulting in a cyclohexane and dimethylpentanes-containing fraction which together with dehexanized-depentanized low end point gasoline heretofore described being passed to the catalytic reforming zone.

Referring now to the drawing, a C₆+ feed, essentially a depentanized low end point gasoline, is passed by conduit 2 into a dehexanizer 4. The bottoms is essentially a fraction containing the cyclohexane and dimethylpentanes with the overhead comprising normal hexane, benzene, and methylcyclopentane and isohexane. The overhead passes through conduit 8 into deisohexanizer 10 from which the isohexanes and lighter fraction is removed overhead through conduit 12. The bottoms pass through conduit 14 into demethylcyclopentanizer 16, the bottoms of which essentially contain cyclohexane and dimethylpentanes which are removed through conduit 18 to join the fraction in conduit 6 to pass to the reformer 46 subsequently described. The overhead from the demethylcyclopentanizer 16 contains essentially methylcyclopentane and small quantities of benzene which pass through conduit 20 to a benzene hydrogenation unit 22 where the feed is contacted with hydrogen (entering through conduit 24 and exiting through conduit 26) under

benzene hydrogenation conditions which will convert substantially all of the benzene to cyclohexane. The effluent from the benzene hydrogenation zone contains essentially cyclohexane, methylcyclopentane, and normal hexane which is passed through conduit 28 into an isomerization zone 30. This methylcyclopentane-isomerization unit catalytically isomerizes the methylcyclopentane to cyclohexane. Any suitable catalyst system may be employed such as an aluminum halide-type catalyst. In addition, some of the n-hexane is isomerized to isohexanes. The isomerization zone effluent is passed by conduit 32 to a demethylcyclopentanizer 34, the overhead which contains isohexanes, normal hexane, and methylcyclopentane which is recycled to the deisohexanizer through conduit 36. The bottoms are passed through conduit 38 to a cyclohexane deoiler 40, the overhead 42 of which is about 98+ percent pure cyclo-

70

hexane. The bottoms are essentially higher boiling materials which are removed from the process through conduit 44.

The feed to the reformer through conduit 6 is now essentially a demethylcyclopentanized low end point gasoline along with a fraction which essentially contains cyclohexane and dimethylpentanes. The reformer conditions are such that the cyclohexane is reformed to produce as high a percentage of methylcyclopentane as possible. Any suitable catalyst, such as platinum-alumina, may be used. A pressure of 200 to 700 p.s.i.g. and a temperature of 850 to 1000° F. is preferred. The effluent from the reformer 46 is essentially methylcyclopentane, benzene, isohexane, some normal hexane, and dimethylpentanes, which is introduced into a depentanizer 50 from which the overhead 52 containing C₅'s and lighter is removed. The bottoms effluent is passed through conduit 54 into a dehexanizer 56. The bottoms stream from the dehexanizer 56 is essentially higher boiling gasoline materials which are removed through conduits 57 and 70. The overhead stream from the dehexanizer is passed through conduit 58 into a zone for the recovery of benzene and the separation of methylcyclopentane from the system. Preferably this zone is a solvent extrac-

This methylcyclopentane is ultimately isomerized to cyclohexane to form the product. The heavies, gasoline components, are removed through conduits 76 and 70.

In summary, the formation of benzene in the reforming step is repressed by the recycling of benzene concentrate to the reforming zone so as to increase the methylcyclopentane yield, with said methylcyclopentane being ultimately recovered as cyclohexane.

The invention is best illustrated by the following example.

EXAMPLE

A material balance of a process using the benzene recycle step (Table I) is compared to the same process without the benzene recycle.

When operating with the benzene recycled to reforming, which is in accordance with my invention, as compared to prior art operation without this benzene recycle, there is a gross profit increase of \$1700.00 per day for the 697 barrels per day (2767 pound mols per day) of benzene which are recycled to extinction. There is, of course, the loss of benzene as product but a gain of 777 barrels per day of cyclohexane product as well as a gain of 77 barrels per day of gasoline.

¹ 98.8 mol percent cyclohexane.

tion zone with benzene being recovered as the extract through conduits 64 and 66. Any means for separation of the benzene may be employed. A suitable solvent is such as triethylene glycol (Udex). A portion of the benzene is then recycled through conduit 68 back into the feed to the reformer 46. The benzene recycle amount is 0.01 to 0.2 mols per mol of feed to reforming. It has been discovered that by recycling this benzene to the reformer that an increase in productivity of the methylcyclopentane which is isomerized to cyclohexane product and a corresponding decrease in the production of benzene is accomplished. Since benzene, at least at present, is less valuable than cyclohexane, this is a desired advantage. The raffinate 72 from the solvent extraction zone contains essentially isohexanes, normal hexane, methylcyclopentane, and heavier boiling materials. This overhead is passed into a dehexanizer 74 from which methylcyclopentane and lighter is recycled through conduit 78 back into the feed for the deisohexanizer 10.

While certain examples, structures, compositions and process steps have been described for purposes of illustration, the invention is not limited to these. Variation and modification within the scope of the disclosure and the claims can readily be effected by those skilled in the art.

I claim:

1. A process for reforming a natural cyclohexane-containing feed which comprises reforming said feed in a reforming zone to produce an effluent containing benzene and methylcyclopentane, recovering benzene from said effluent and recycling said benzene to said reforming zone.

2. A process for reforming a natural cyclohexane-containing feed also containing dimethylpentanes comprising reforming said feed in a reforming zone to produce an effluent containing benzene and methylcyclopentane, recovering benzene from said effluent, recycling said benzene to said reforming zone, recovering a first fraction

from said effluent containing methylcyclopentane and dimethylpentanes and recovering methylcyclopentane from said first fraction.

3. A process for increasing the purity of methylcyclopentane produced by the reforming of a natural cyclohexane-containing feed also containing dimethylpentanes, n-hexane, benzene, and methylcyclopentane which comprises recovering from said feed a first fraction containing the cyclohexane and dimethylpentane, reforming said first fraction, recovering from the reforming zone effluent a second fraction containing benzene, recycling said second fraction to said reforming zone, recovering from said reforming zone effluent a third fraction containing methylcyclopentane, benzene, isohexanes, n-hexane, and dimethylpentanes and heavier, and recovering from said third fraction methylcyclopentane.

4. A process for the production of methylcyclopentane from a natural cyclohexane-containing feed also containing dimethylpentanes, n-hexane, benzene, and methylcyclopentane which comprises recovering from said feed a first fraction containing n-hexane, benzene and methylcyclopentane leaving a second fraction containing the cyclohexane and dimethylpentanes, reforming said second fraction, recovering from the reforming zone an effluent containing methylcyclopentane, benzene, isohexanes, n-hexane, dimethylpentanes and heavier, recovering heptanes and heavier from said effluent, recovering a third fraction containing benzene from said effluent in a solvent extraction zone, recycling said third fraction to said reforming zone, and recovering a fourth fraction from said extraction zone containing methylcyclopentane, n-hexane, dimethylpentanes and heavier, and recovering a methylcyclopentane fraction from said fourth fraction.

5. A process for the production of cyclohexane from

a natural cyclohexane-containing feed also containing dimethylpentanes, n-hexane, benzene, and methylcyclopentane which comprises recovering from said feed a first fraction containing n-hexane, benzene and methylcyclopentane leaving a second fraction containing the cyclohexane and dimethylpentane, reforming said second fraction, recovering from the reforming zone an effluent containing methylcyclopentane, benzene, isohexanes, n-hexane, dimethylpentanes and heavier, recovering heptanes and heavier from said effluent, recovering a third fraction containing benzene from said effluent in a solvent extraction zone, recycling said third fraction to said reforming zone, and recovering a fourth fraction from said extraction zone containing methylcyclopentane, n-hexane, dimethylpentanes and heavier, recovering a methylcyclopentane fraction from said fourth fraction, subjecting said first fraction and said methylcyclopentane fraction together and in the presence of each other in a benzene-hydrogenation zone to benzene-hydrogenation conditions, recovering a hydrogenation zone effluent, then subjecting the hydrogenated effluent in an isomerization zone to methylcyclopentane-isomerization conditions, and then recovering a high-purity cyclohexane from the isomerization zone effluent.
